UNITED STATES PATENT OFFICE

134,944

DESIGN FOR A VEHICLE BODY

Albert Mortimer, Superior, Wis.

Application August 14, 1942, Serial No. 107,934

Term of patent 7 years

To all whom it may concern:

Be it known that I, Albert Mortimer, a subject of the King of England, residing in Superior, county of Douglas, and State of Wisconsin, have invented a new, original, and ornamental Design for a Vehicle Body, of which the following is a specification, reference being had to the accompanying drawing, and forming part thereof.

In the drawing:

I claim:

The ornamental design for a vehicle body, as shown.

ALBERT MORTIMER.
